PAD ANTI-RATTLE SPRING FOR A DISC BRAKE

Norbert Kolb, Neuwied, Germany, assignor to
Girling Limited, Birmingham, England

Filed May 9, 1975, Ser. No. 576,119

Claims priority, application Great Britain Nov. 27, 1974

Term of patent 14 years

Int. Cl. D12—16

U.S. Cl. D12—180

FIG. 1.

FIG. 2.

FIG. 3.

FIG. 1 is a perspective view showing the underside of a pad anti-rattle spring for a disc brake embodying my new design;

FIG. 2 is a perspective view showing the top thereof; and

FIG. 3 is an end elevational view thereof.

I claim:

The ornamental design for a pad anti-rattle spring for a disc brake, as shown.
